UNITED STATES PATENT OFFICE.

ALICE M. ANDERSON, OF ST. LOUIS, MISSOURI.

STENOTYPE-KEYBOARD.

1,143,160.

Specification of Letters Patent. Patented June 15, 1915.

Application filed June 17, 1914. Serial No. 345,585.

To all whom it may concern:

Be it known that I, ALICE M. ANDERSON, a citizen of the United States, residing at the city of St. Louis, State of Missouri, have 5 invented a certain new and useful Improvement in Stenotype-Keyboards, of which the following is a full, clear, and exact description, such as will enable others skilled in the art to which it appertains to make and use 10 the same, reference being had to the accompanying drawings, forming part of this specification.

My invention relates to certain new and useful improvements in keyboards for writing machines, and is designed particularly with reference to the stenographic writing machine built under the Ireland patents, and commercially known as the "Stenotype".

This machine is characterized by the use 20 of a permutation keyboard having a spacing bar, a centrally arranged bank of vowel keys manipulated by the thumbs of the operator, a left hand double bank of consonant keys manipulated by the fingers of the left hand, 25 and a right hand double bank of consonant keys manipulated by the fingers of the right hand. The words or word outlines are written by the simultaneous depression of a plurality of keys by both hands, the keys manipulated by the left hand printing the initial or first letters of a word or outline, and the keys operated by the right hand printing the other letters of the word or outline.

In operating the machine, it is necessary 35 for the operator to move his fingers into a great number of different positions and depress all of the keys which are to be operated simultaneously. Because of the rapidity with which the work must be done and the 40 unusual and difficult positions which must be assumed by the fingers of the operator, the proper manipulation of the machine is necessarily difficult.

It is the purpose of my invention to provide 45 a form of keyboard which, due to its contour, and the form of the individual keys, will greatly facilitate the operation of the machine and enable the operator to accomplish more rapid and accurate work with 50 less muscular effort and nervous strain. This I do by shaping the tops or striking surfaces of the keys in such fashion as to render them more easily operable by the various fingers of the operator, particularly 55 in the striking of difficult combinations, and

forming them with reference to one another in such fashion as to insure an accurate operation of a combination of keys by a single finger.

The drawings illustrate in Figure 1, a 60 plan view of the machine; in Fig. 2, a front view showing my improved keyboard; in Fig. 3, a section on line 3—3 of Fig. 1; in Fig. 4, a section on line 4—4 of Fig. 1; in Fig. 5, a section on line 5—5 of Fig. 1; in Fig. 6, a section on line 6—6 of Fig. 1; in Fig. 7, a section on line 7—7 of Fig. 1; in Fig. 8, a section on line 8—8 of Fig. 1; in Fig. 9, a section on line 9—9 of Fig. 1; in Fig. 10, a section on line 10—10 of Fig. 1; in Fig. 11, a section on line 11—11 of Fig. 1.

As illustrated in Fig. 1, the letter keys, twenty-one in number, are marked with indicative letters, by which they hereinafter will be identified with the further addition of a 75 minus (—) sign before symbols indicating keys in the right hand bank which are duplicated in the left hand bank.

In the operation of the machine, the spacing key is designated by the numeral 3. The vowel keys A, O, E, U, are operated by the thumbs. The H and R keys by the index finger of the left hand. The P and W keys by the middle finger of the left hand. The T and K keys by the ring finger of the left 80 hand, and the S key by the little finger of the left hand. In the right hand bank, the F and —R keys are always manipulated by the index finger, the —P and B keys by the middle finger, the L and G keys by the ring 85 finger, the —T and —S, —D, and —S by the little finger, all of the right hand. In addition there is the asterisk bar 4 operable by any of the fingers. It will be obvious, then, that the shortest finger, to wit, the little finger, has to make the longest reaches, and its work is rendered difficult by having to work in coöperation with the longer 90 fingers which have to reach shorter distances. It is necessary to compensate for the insufficient length of the little finger by moving the wrists, which movement throws the hand and elbow of the operator out of their proper position over the keyboard, rendering necessary compensating movements on the 95 part of the other fingers. By the use of my improved keyboard, all of these difficulties are obviated.

As is shown in Fig. 2, and in the sectional views, I form the key tops so that the strik- 100 105 110

ing surfaces of the keys which are to be operated by the shorter fingers are raised relative to the plane of the keys operated by the longer fingers, thereby enabling the operator to strike any key by simple finger movement without changing the position of the wrists, hands, or elbows.

As shown in Figs. 2, 5, and 8, the P, W, -P, and B keys, which are manipulated by the middle fingers, are arranged at the lowest elevation. These keys have their striking surfaces concaved from side to side, and inclined toward each other. The concavity of the striking surfaces tends to prevent the fingers of the operator from slipping off the key tops sidewise. The inclination of the striking surfaces toward the adjacent edges of the keys in front or rear of them, forms a depression for the finger of the operator at the adjacent edges of the keys, which facilitates the striking of two keys such as the P and W or the -P and B keys, as the case may be, simultaneously by a single finger, and insures a full stroke of both the keys so operated by a single finger. The H and F keys which are designed to be manipulated by the index fingers have their striking surfaces arranged at substantially the same elevation, their striking surfaces concaved, and inclined forwardly toward the R and -R keys, respectively, which are also designed to be operated by the index fingers. The R and -R keys are similar and have their striking surfaces inclined toward the H and F keys, respectively, for the purpose, as above indicated, of facilitating the striking of the juxtaposed keys simultaneously by a single finger. A further purpose in thus elevating the front portions of such keys as the S, K, R, -R, and -S keys, is to oppose any tendency of the fingers of the operator to slip off thereof during manipulation of the keys in difficult finger positions. The T and L keys have substantially the same elevation and conformation as the H key.

The -T and D keys, being operated by the little finger of the right hand, are raised to the highest elevation of any of the keys, and they, like the others, have concaved striking surfaces sloped forwardly to meet the -S keys. The -S keys are identical, and are sloped rearwardly toward the -T and D keys. The S key, which is the long key extending the entire depth of the upper keyboard, has its striking surface concaved and synclined toward its center. The striking surface is raised into position where it is easily reached and the key operated by the little finger of the left hand.

The G key is distinct from all the others, in that while its striking surface is concaved, it is not raised at its forward edge, but it is sloped inwardly toward the L key at its rear edge. The purpose of giving the G key this

conformation is to facilitate the striking of such difficult combinations as BGD which represent the ending "ked" in words such as "liked" or such combinations as GD, BGT, or GT, all of frequent use. In striking these combinations, it will be noted that it is necessary to strike the G key which is in the front series, simultaneously with one or more keys in the rear series. In order to avoid movement of the wrists or forearms, it becomes necessary to curve the ring finger backwardly under the palm to strike the G key while the small finger is extended forwardly to strike the T or D key. The form of the G key described, facilitates its operation by the ring finger in this position, it being noted that the key is really struck with the nail or back of the finger.

The surface contour of the G key above described, permits the ring finger taking this position without interference or possible manipulation of that key. The extra elevation of the T and D keys facilitates the striking of words ending in "nt" (PBT) and "nd" (PBD), which endings occur in about twenty-two per cent. of words ordinarily encountered in using the machine. The conformation of these keys in this fashion obviates the necessity of moving the elbow outwardly for the purpose of avoiding interference with the S keys, when these combinations are struck. Based on the above noted percentage, it will be seen that at an ordinary speed of two hundred words per minute, it will be necessary to make this extra arm movement forty-four times in a minute. This is all obviated by the construction of the keys in the fashion shown.

The asterisk bar 4 is operated in conjunction with others of the keys and simultaneously therewith, as for instance, to print the numerals 1, in which it is depressed simultaneously with the S key, 2, in which it is depressed simultaneously with the T key, etc. Consequently, the adjacent portions of the asterisk bar are raised so as to dispose the striking surfaces at the elevation of the adjacent keys whereby the bar may be operated simultaneously with such keys by the same finger.

It will be seen that in nearly all instances the rear keys have their striking surfaces disposed at considerably greater elevation than the keys in front of them. This makes it unnecessary for the operator to move his hands rearward over the keyboard to reach the rear keys, and also enables him to operate the rear keys without interfering with the keys in the front bank. Furthermore the disposal of the striking surfaces of different keys to compensate for the difference in length of the operator's fingers, enables the operator to operate all the keys with a uniform length of stroke or depression, no matter what combination is struck. As a

result the printed characters will be uniform as to density or shade, and the condition of having some of the characters light and others heavy, avoided.

5 It will be understood from the foregoing, therefore, that my invention provides a keyboard arrangement in which the various keys conform to the reach of various fingers, and thereby render it unnecessary for the operator to change the position of his hands, wrists, or elbows, in striking the various combinations. This relieves the operator of much muscular effort and nervous strain. Furthermore, the elevation of the various 10 keys obviates the liability of the operator's fingers interfering with keys other than those selected while moving into position to strike a combination.

15 Likewise the inclination of the striking surfaces tends to inhibit the fingers of the operator from slipping off of the keys, and the inclination toward each other of the striking surfaces of longitudinally aligned keys, provides a striking point at the juxtaposed portions of such keys which is easily found by the finger of the operator, and which insures simultaneous operation of such keys by the same finger when desired.

20 I am aware that my invention may be embodied in forms differing in particulars from those illustrated without departing from the scope of the invention. I am aware, furthermore, that the permanent keys of the machine may be made with their 25 striking surfaces disposed as described, or that the keys may be provided with striking pads or auxiliary tops having the striking surfaces so arranged. It is not my intention, therefore, that my invention be limited 30 to the specific form shown, but that it include all obvious changes and modifications properly within its spirit and scope.

What I claim is:

1. In a machine of the class described, a 35 plurality of type-actuating keys disposed in juxtaposed series; different keys in the same series having their striking surfaces arranged in different horizontal planes, and juxtaposed keys in the different series having portions of their striking surfaces sloped toward each other to the same horizontal

plane and other portions thereof in different horizontal planes.

2. In a machine of the class described, a plurality of type-actuating keys arranged in 55 different series, keys in the different series being juxtaposed for simultaneous operation; respective keys of a series having their striking surfaces disposed in different horizontal planes, and juxtaposed keys in different series having portions of their striking surfaces sloped toward each other to the same horizontal plane.

3. In a machine of the class described, juxtaposed keys adapted to be operated by 65 the same finger of the operator, said keys being arranged with their striking surfaces converged to form a striking point for the finger in simultaneous operation of said keys, and with other portions of their striking surfaces arranged at different relative elevations for individual manipulation.

4. In a machine of the class described, a keyboard having juxtaposed transverse series of keys, keys in the rear series being arranged with their striking surfaces at a greater elevation than the striking surfaces of keys in the front series, and sloping downwardly to the level of the adjacent striking surfaces of keys in the front series and keys 80 in the front series having their striking surfaces sloped rearwardly, to provide a striking point whereat keys in both series may be simultaneously and uniformly operated by a single finger of the operator. 85

5. In a machine of the class described, a keyboard containing juxtaposed transverse series of keys, keys in the respective series being arranged with their striking surfaces synclined toward each other for the purpose 90 of forming a striking point to facilitate the uniform operation of keys in both series simultaneously by a single finger of the operator.

In testimony whereof I hereunto affix my 95 signature in the presence of two witnesses, this 8th day of June, 1914.

ALICE M. ANDERSON.
